FIG. 1

FIG. 2

Karrison H. Boyce INVENTOR.
BY *Lefford I. Dunn* ATTORNEY

UNITED STATES PATENT OFFICE.

HARRISON H. BOYCE, OF FOREST HILLS, NEW YORK.

DESIGN FOR A CASING FOR AUTOMOBILE-RADIATOR INDICATORS.

48,707.

Specification for Design.

Patented Mar. 14, 1916.

Application filed August 28, 1915. Serial No. 47,867. Term of patent 14 years.

To all whom it may concern:

Be it known that I, HARRISON H. BOYCE, a citizen of the United States, residing at Forest Hills, in the borough and county of Queens, city and State of New York, have invented a new, original, and ornamental Design for a Casing for Automobile-Radiator Indicators, of which the following is a specification, reference being had to the accompanying drawings, forming a part hereof.

Referring to the annexed sheet of drawing, Figure 1 represents a front elevation of a casing for automobile radiator indicators embodying my new design. Fig. 2 is a side view thereof.

I claim:

The ornamental design for a casing for automobile radiator indicators as shown.

HARRISON H. BOYCE.
